5 Claims. (Cl. 101—278)

1

This invention relates to printing machines wherein a sheet fed to an impression cylinder is carried thereby into contact with a printing surface and, after printing, the sheet is delivered from the impression cylinder. The invention is particularly applicable to a printing machine wherein the impression cylinder co-operates with a printing surface mounted on a reciprocating printing bed, the impression cylinder normally remaining continuously in position for receiving an impression.

According to the invention there is provided a printing machine having a reciprocating printing bed carrying a printing surface and having an impression cylinder co-operating therewith wherein the impression cylinder is provided with a plurality of separate surfaces comprising an impression surface which carries a sheet into contact with the printing surface for printing, a transfer surface to which the sheet is transferred after printing for delivery from the machine, and a surface which is cut-away to avoid contact with the surface on the printing bed during the reverse or non-printing stroke thereof. The sheet may be taken from the impression surface and transferred to the transfer surface by means of a transfer cylinder which makes one revolution while taking a sheet from the impression surface, another revolution while transferring the sheet to the transfer surface and an idle revolution while co-operating with the cut-away surface of the impression cylinder.

The transfer cylinder may be provided with sheet grippers which are operated so that during one revolution a sheet is taken from the impression surface and during the next revolution a sheet is released and transferred to the transfer surface, said grippers remaining inoperative during the idle revolution of the transfer cylinder. Operation of the sheet grippers may be controlled by a cam provided on a driven shaft on which the driven transfer cylinder is freely mounted, the shaft making one revolution for three revolutions of the transfer cylinder.

The invention will now be described in greater detail with reference to the accompanying drawings, which illustrate one form which it may assume.

In the said drawings:

Figure 1 is a side elevation of the relevant parts of a printing machine constructed according to the present invention;

Figure 2 is an enlarged plan view of the transfer cylinder and its associated operating mechanism;

2

Figure 3 is an enlarged side view of the cams by means of which the transfer cylinder grippers are operated;

Figure 4 is a section taken on the line IV—IV of Figure 3;

Figure 5 is a section taken on the line V—V of Figure 2;

Figure 6 is a side view of the transfer cylinder. Referring to Figure 1, a printing surface comprising a type forme 1 is mounted on a printing bed 2 which is reciprocated along tracks 3 carried by a machine frame 4. The upper part of the machine frame 4 has side members 5 carrying eccentric bearings 6 for the shaft 7 of an

impression cylinder 8 to which sheets are fed from the feedboard F for printing. The bearings 6 are normally stationary so that the impression cylinder 8 remains continuously in position for receiving an impression. If it is desired to trip the impression cylinder 8 out of contact with the type forme 1 (as in the event of the incorrect feeding of a sheet), the eccentric bearings 6 are rotated through movement of the rod 9 and arm 10 connected to each bearing.

25 The diameter of the impression cylinder 8 is three times that of a transfer cylinder 11 with which it cooperates, and the circumference of the impression cylinder 8 is divided into three parts comprising an impression surface 12, a

30 transfer surface 13 and a cut-away portion 14. To provide the cut-away portion 14 a part of the impression cylinder bearers 15 is removed which would otherwise contact with the bearers 16 on the printing bed 2 during the reverse or non-

35 printing stroke of the bed, and a part of the surface of the impression cylinder 8 is made approximately one-eighth of an inch below the impression surface 12 so that the type forme 1 on the bed 2 can pass freely during the reverse stroke

40 of the bed without contacting with the surface of the impression cylinder 8.

The impression cylinder 8 is driven through gearing by the main driving shaft of the machine, and is provided with a gear 17 which meshes with a gear 18 on the body of the transfer cylinder 11.

For taking a sheet on the impression surface 12 and subsequently delivering it to the transfer cylinder 11, grippers 19 (hereinafter referred to as impression cylinder grippers) are mounted on a gripper shaft 20 carried by the impression cylinder 8, said gripper shaft 20 being provided with a tumbler 21 engaging opening and closing pins 22, 23, carried by the machine frame 4. For taking a sheet from the transfer cylinder 11 on to

the transfer surface 13 and subsequently delivering it to grippers 24 on a delivery chain 25, grippers 26 (hereinafter referred to as impression cylinder transfer grippers) are provided on a shaft 27 having a cam lever 28 carrying a roller 29 which engages opening and closing cams 30, 31, carried by the framework.

The transfer cylinder 11, which is provided with a sheet receiving surface 32, is carried by a shaft 33 supported in transfer cylinder brackets 34, comprising side members rigidly connected together by tie rods 35, the brackets 34 being secured by means of bolts to the framework 4 of the machine. As is hereinafter more fully described, the brackets 34 carry mechanism associated with the operation of the transfer cylinder 11, and the described construction and arrangement of the brackets 34 facilitates the assembly of the transfer cylinder 11 and associated mechanism as a complete unit which can be readily removed and replaced.

The transfer cylinder body has secured thereto at each end, a bush 36 (see Figure 2) and is freely mounted on the transfer cylinder shaft 33, which is rotatably carried in bushes 37 secured to the transfer cylinder brackets 34. The gear 18 secured to the transfer cylinder body and meshing with the gear 17 on the impression cylinder 8 has a diameter one-third that of the gear 17. The transfer cylinder shaft 33 is driven by the transfer cylinder 11 through an epicyclic train of gearing comprising a fixed gear 38 attached to a side member of the transfer cylinder brackets 34, a compound pinion 39a, 39b (see Figure 5) freely mounted on a stud 40 secured to the transfer cylinder body and a gear 41 keyed to the transfer cylinder shaft 33. The larger member 39a of the compound pinion meshes with the fixed gear 38 and the smaller member 39b meshes with the gear 41 on the shaft 33. The value of the gear train is such that the transfer cylinder shaft 33 rotates in a direction opposite to the direction of rotation of the transfer cylinder 11 at one-third of the rotational speed thereof. As the transfer cylinder 11 is geared to the impression cylinder 8 and makes three revolutions for one revolution of the impression cylinder 8, it follows that the transfer cylinder shaft 33 will make one revolution for one revolution of the impression cylinder 8, or in other words, one revolution per impression.

A gripper shaft 42 (see Figure 6) is supported in bearings on the transfer cylinder body 11 and is provided with a cam lever 43 and cam roller 44. Grippers 45 are clamped to the gripper shaft 42 and close on to a bar 46 secured to the transfer cylinder body. Gripper pressure is derived from a spring 47 which slides freely on a spring supporting rod 48 which is pin-jointed to the gripper shaft 42. The lower end of the spring rod 48 slides freely in a hole in the transfer cylinder body 11 and the spring 47 is compressed between a shoulder 49 at the upper end of the spring supporting rod 48 and a boss 50 in the cylinder body. A projection 51 on the cam lever 43 engages a peg 52 projecting from the end of the transfer cylinder body to limit the rotation of the gripper shaft 42 when the grippers 45 are adjusted on the shaft 42.

For operating the cam lever 43, two cams 53, 54 (see Figures 3 and 4) each having the form of a portion of a disc with co-axial cylindrical projections 55, 56, perpendicular to the plane surfaces of the cams 53, 54, are slidably mounted in a bracket 57 which is either an integral part

of, or is secured to, one of the side members of the transfer cylinder bracket 34.

Each cam 53 or 54 is furnished with a stud 58 or 59 carrying a roller 60 or 61 adapted to engage with a grooved cam 62 secured to the transfer cylinder shaft 33. The shape of the grooved cam 62 is such as to impart an intermittent reciprocating movement to the two cams 53, 54, which are thus alternately moved in a direction parallel to the transfer cylinder shaft 33 to and from an operative position in which said cams 53, 54 may be engaged by the roller 44 of the cam lever 43 on the gripper shaft 42. Each of the cams 53, 54 is guided by means of a bracket 63 and is prevented from rotating by the boss 64 of the bracket 57 in which the cams 53, 54 are slidably mounted.

The two cams 53, 54 are symmetrically placed relatively to a horizontal line passing through the centre of the transfer cylinder shaft 33. The roller 60 carried by one cam 53 located above the horizontal line is inclined at an angle of 60° to such line, and the roller 61 carried by the other cam 54 located below the horizontal line is also inclined at angle of 60° to such line. That is to say, the mutual angular displacement of the rollers is 120° corresponding to one-third of a revolution of the transfer cylinder shaft 33, or one revolution of the transfer cylinder 11.

Thus the reciprocation of one cam 53 to and from the operative position in which the transfer cylinder grippers 45 are opened and closed on to a sheet to take the sheet from the impression cylinder grippers 19, is followed on the succeeding revolution of the transfer cylinder 11 by the reciprocation of the other cam 54 to and from the operative position in which the transfer cylinder grippers 45 are opened to release the sheet and allow the impression cylinder transfer grippers 26 to transfer the sheet to the transfer surface 13 of the impression cylinder 8.

In operation a sheet fed to the impression cylinder 8 is taken by the impression cylinder grippers 19 on to the impression surface 12 and is carried thereby for printing into contact with the type forme 1. After printing, the transfer cylinder grippers 45 are opened to receive the printed sheet from the impression cylinder grippers 19 which are now in the position shown in Figure 1. After the transfer cylinder grippers 45 have closed on to the sheet the impression cylinder grippers 19 are opened.

As the impression cylinder 8 and transfer cylinder 11 rotate the sheet is transferred to the sheet receiving surface 32 on the transfer cylinder 11. Continued rotation of the cylinders 8 and 11 brings the normally closed impression cylinder transfer grippers 26 to a position approaching the transfer cylinder grippers 45. The impression cylinder transfer grippers 26 are then opened and closed on to the leading end of the sheet carried by the sheet receiving surface 32, and immediately afterwards the transfer cylinder grippers 45 open to release the sheet. During further rotation of the cylinders 8 and 11, the sheet is transferred to the transfer surface 13 of the impression cylinder 8.

While the sheet is being taken by the transfer surface 13 the cut-away portion 14 of the impression cylinder 8 approaches the position in which the printing bed 2 can make a reverse stroke without contacting with the impression cylinder 8. Also at this time another sheet is being fed to the impression surface 12 of the impression cylinder 8. Continued rotation of

the impression cylinder 8 brings the impression cylinder transfer grippers 26 to a position in which they are opened to allow the sheet to be taken by the grippers 24 on the delivery chain 25. While the sheet is being delivered, the second sheet fed to the impression surface 12 is receiving an impression from the type forme 1 on the printing bed 2 which has commenced its printing stroke. Also at this time the cut-away portion 14 of the impression cylinder 8 is co-operating with the transfer cylinder 11 which is making an idle revolution.

Having thus described our invention, we declare that what we claim and desire to secure by Letters Patent is:

1. In a printing machine, the combination with a reciprocating printing bed carrying a type forme of a rotating impression cylinder which is successively provided around the periphery thereof with an arcuate impression surface, a separate arcuate transfer surface, both of said surfaces having equal radii, and a separate arcuate surface having a radius which is less than that of the said impression and transfer surfaces to permit a reverse non-printing stroke of the printing bed, sheet gripper mechanism on said impression cylinder and associated with said impression and transfer surfaces, means for operating said sheet gripper mechanism to receive and release a sheet on said impression surface and to receive and release a sheet on said transfer surface, a transfer cylinder co-operating with said impression cylinder and having formed thereon a sheet-receiving surface, sheet gripper mechanism on said transfer cylinder and associated with said sheet receiving surface, means for operating said sheet gripper mechanism on the transfer cylinder to receive a sheet released from the impression surface on the impression cylinder and to release a sheet to be received by the transfer surface of the impression cylinder, means for feeding a new sheet to said impression surface on the impression cylinder after a previous sheet has been completely transferred therefrom to the sheet receiving surface on the transfer cylinder, and means for delivering such previous sheet which is released from the transfer surface on the impression cylinder after being completely transferred thereto from the sheet-receiving surface on the transfer cylinder.

2. In a printing machine, the combination with a reciprocating printing bed carrying a type forme of a rotating shaft, an impression cylinder mounted on said shaft and being successively provided around the periphery thereof with an arcuate impression surface, a separate arcuate transfer surface, both of said surfaces having equal radii, and a separate arcuate surface having a radius which is less than that of the said impression and transfer surfaces to permit a reverse non-printing stroke of the printing bed, sheet gripper mechanism on said impression cylinder and associated with said impression and transfer surfaces, means for operating said sheet gripper mechanism to receive and release a sheet on said impression surface and to receive and release a sheet on said transfer surface, a transfer cylinder cooperating with said impression cylinder and having formed thereon a sheet-receiving surface, said transfer cylinder having a diameter which is approximately one-third the diameter of the said impression cylinder, a transfer cylinder shaft on which the transfer cylinder is mounted, said shaft being located approximately in the same horizontal plane as the shaft on which the said im-

pression cylinder is mounted, sheet gripper mechanism on said transfer cylinder and associated with said sheet receiving surface, means for operating said sheet gripper mechanism on the transfer cylinder to receive a sheet released from the impression surface on the impression cylinder and to release a sheet to be received by the transfer surface of the impression cylinder, means for feeding a new sheet to said impression surface on the impression cylinder after a previous sheet has been completely transferred therefrom to the sheet receiving surface on the transfer cylinder, and means for delivering such previous sheet which is released from the transfer surface on the impression cylinder after being completely transferred thereto from the sheet-receiving surface on the transfer cylinder.

3. In a printing machine, the combination with a reciprocating printing bed carrying a type forme of a rotating impression cylinder which is successively provided around the periphery thereof with an arcuate impression surface, a separate arcuate transfer surface, both of said surfaces having equal radii, and a separate arcuate surface having a radius which is less than that of the said impression and transfer surfaces to permit a reverse non-printing stroke of the printing bed, sheet gripper mechanism on said impression cylinder and associated with said impression and transfer surfaces, means for operating said sheet gripper mechanism to receive and release a sheet on said impression surface and to receive and release a sheet on said transfer surface, a transfer cylinder driven by said impression cylinder and having formed thereon a sheet-receiving surface, sheet gripper mechanism on said transfer cylinder and associated with said sheet-receiving surface, a shaft on which said transfer cylinder is loosely mounted, means for rotating said shaft by rotation of said transfer cylinder, cam mechanism on said shaft controlling the operation of the said sheet gripper mechanism on the transfer cylinder to permit said gripper mechanism to receive a sheet released from the impression surface on the impression cylinder and to release a sheet to be received by the transfer surface of the impression cylinder, means for feeding a new sheet to said impression surface on the impression cylinder after a previous sheet has been completely transferred therefrom to the sheet-receiving surface on the transfer cylinder and means for delivering such previous sheet which is released from the transfer surface on the impression cylinder after being completely transferred thereto from the sheet-receiving surface on the transfer cylinder.

4. In a printing machine, the combination with a reciprocating printing bed carrying a type forme of a rotating shaft, an impression cylinder mounted on said shaft and being successively provided around the periphery thereof with an arcuate impression surface, a separate arcuate transfer surface, both of said surfaces having equal radii, and a separate arcuate surface having a radius which is less than that of the said impression and transfer surfaces to permit a reverse non-printing stroke of the printing bed, sheet gripper mechanism on said impression cylinder and associated with said impression and transfer surfaces, means for operating said sheet gripper mechanism to receive and release a sheet on said impression surface and to receive and release a sheet on said transfer surface, a transfer cylinder driven by said impression cylinder and having formed thereon a sheet-receiving surface, said transfer cylinder having a diameter which is approximately one-third the diameter of the said impression cylinder, a transfer cylinder shaft on which the transfer cylinder is mounted, said shaft being located approximately in the same horizontal plane as the shaft on which the said im-

pression cylinder is mounted, sheet gripper mechanism on said transfer cylinder and associated with said sheet receiving surface, means for operating said sheet gripper mechanism on the transfer cylinder to receive a sheet released from the impression surface on the impression cylinder and to release a sheet to be received by the transfer surface of the impression cylinder, means for feeding a new sheet to said impression surface on the impression cylinder after a previous sheet has been completely transferred therefrom to the sheet receiving surface on the transfer cylinder, and means for delivering such previous sheet which is released from the transfer surface on the impression cylinder after being completely transferred thereto from the sheet-receiving surface on the transfer cylinder.

sheet-gripper mechanism on said transfer cylinder and associated with said sheet-receiving surface, a shaft on which said transfer cylinder is loosely mounted, a gear wheel secured to said shaft, a compound pinion mounted on the side of said transfer cylinder and having one member thereof meshing with the said gear wheel, a fixed gear wheel with which the other member of said compound pinion engages so as to rotate said shaft by rotation of said transfer cylinder, cams secured to said shaft and controlling the operation of the said sheet-gripper mechanism on the transfer cylinder to permit said gripper mechanism to receive a sheet released from the impression surface on the impression cylinder and to release a sheet to be received by the transfer surface of the impression cylinder, means for feeding a new sheet to said impression surface on the impression cylinder after a previous sheet has been completely transferred therefrom to the sheet-receiving surface on the transfer cylinder, and means

for delivering such previous sheet which is released from the said transfer surface on the impression cylinder after being completely transferred thereto from the sheet-receiving surface on the transfer cylinder.

5. In a printing machine, the combination according to claim 4 including a framework in which the transfer cylinder shaft and the fixed gear wheel are mounted, said framework being detachably secured to the printing machine framework.
